DIE HOLDING AND LUBRICATING
MECHANISM

Walter E. Rogers, Stow, and Norman H. Nye,
Cuyahoga Falls, Ohio, assignors to The Vaughn
Machinery Company, Cuyahoga Falls, Ohio, a
corporation of Ohio

Application April 1, 1946, Serial No. 658,762

6 Claims. (Cl. 205—19)

1

The present invention relates to improvements in a wire draw bench or the like and more particularly to the die holding and lubricating mechanism thereof.

As is well known in the drawing of wire it is essential that a lubricant be supplied to the wire at the point where it passes through a die hole in order to prevent excessive heating of the wire and of the die. Lubrication is also essential to produce a scratch-free, smooth, bright surface on the wire and to produce a wire of uniform size. One common method of lubricating is to flood the wire or the die with lubricant, but, of course, such method necessitates the use of a considerable excess of lubricant in order to insure the desired results. On the other hand, if a fine stream or jet of lubricant as delivered through a small orifice were used to reduce such excess, either expensive filters would have to be employed to prevent foreign matter from clogging such orifice or else such clogging would have to be contended with and accompanied by periodic stopping of the drawing operation to clear any clogged orifices.

Accordingly, it is one principal object of this invention to provide a simple form of die holding and lubricating device having a small orifice therein for conducting a fine stream of lubricant to a die, which orifice can be cleared out at will within a fraction of a second simply by flicking the device out of die engaging position without the necessity of interrupting the continuous drawing operation.

It is another object of this invention to provide a device in which a single yielding means is operative to hold a die seated in a support therefor and to maintain the orifice clearing means associated therewith in an inoperative position.

Additional objects and advantages of the invention will become apparent as the following description proceeds.

To the accomplishment of the foregoing and related ends, said invention then comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In the drawing:

Fig. 1 is a front elevation view of a portion of a continuous type wire drawing bench showing

one of the die holding and lubricating devices in longitudinal cross section;

Fig. 2 is a transverse vertical cross section of the draw bench and one of the die holding and lubricating devices taken along line 2—2 of Fig. 1;

Fig. 3 is an end view of one of the die holding and lubricating devices alone as viewed from the top of Fig. 1 and showing the die support and die dotted; and

Fig. 4 is a front elevation view of a portion of the draw bench with one of the die holding and lubricating devices in longitudinal cross section and showing such device in a position out of engagement with the die and with the orifice clearing means projected through an orifice in such device.

The draw bench illustrated in the drawing is of the continuous type wherein the wire being drawn is successively drawn through a series of dies and is gradually reduced in cross section size without the necessity of performing one reduction in size and after each such reduction removing the completed coil and setting up such coil on another draw bench for performing a succeeding reduction. The number of reductions required, of course, depends on the total reduction in size and the properties desired in the finished wire. In such continuous draw benches it is necessary to provide a power rotated block or drum behind each die with the wire wound thereabout a sufficient number of times so that the drum can frictionally draw the wire through the hole in the next preceding die and, of course, each drum must be driven faster than

the next preceding one in order to compensate for the elongation of the wire as it is being drawn through the dies and being reduced in cross section size. While in the drawing there is shown a draw bench of the continuous type, it is to be understood that the die holding and lubricating device can be used with equal facility in "single draft" draw benches wherein the wire is subjected only to one reduction.

In detail the draw bench herein illustrated comprises a vertically disposed base portion 1 which rotatably supports one or more power driven blocks or drums 2 and which has projecting therefrom a series of supports 3, one preceding each drum 2 and each being provided with a die seat or die receiving recess 4 therein for a die 5. Each die 5 has a flared hole 6 therein of the usual form providing a smoothing out section, a bearing section and a countersunk section and, in a multi-reduction draw bench such

as shown, the hole 6 in each successive die is smaller than that in the next preceding one by an amount limited by the strain which the reduced wire will stand and also by other factors such as the final desired physical properties of the wire. The die holes 6 are arranged so that a straight piece of wire passed therethrough will be tangent to the outer surface of the next following drum 2.

Below the base portion 1 is a lubricant containing manifold 7 which has through one wall thereof of several aligned openings disposed substantially directly below the supports 3, such openings each having a die holding and lubricating member 8 pivotally mounted therein. In the present case such pivotal mounting is accomplished by forming one end of the member 8 with a cylindrical extension 9 projected through such opening and terminating in a shoulder 10 having a face thereof adjacent to and overlying the outer wall of the manifold 7. Member 8 is held against axial movement relative to such opening by means of a split retainer ring 11 engaged in a groove adjacent the end of such cylindrical extension 9, such ring 11 overlying the inner wall of the manifold 7.

Member 8 is hollow and has at its upper end an orifice 12 directed upwardly and inclined toward the die hole 6 when said member is in die engaging position. Coaxial with such orifice 12 in member 8 is a passage 13 in which a rod 14 is slidably mounted, said rod including a reduced end 15 which is projectable through orifice 12 for clearing the same. In order to normally maintain the rod end 15 out of projected position through the orifice 12 a spring 16 is provided which surrounds rod 14 and bears against member 8 and the shoulder defined by the enlarged head 17 of the rod. In order that the spring 16 will also function to yieldably hold the die 5 in its support 3, the outer end of each rod is arranged to bear against a fixed support 18 projecting from the front wall of the manifold 7. Thus, as shown in Fig. 1, the spring 16 urges the rod 14 against support 18 and the upper end of member 8 against the die 5 thereby holding the end 15 of the rod away from orifice 12 and holding die 5 in its support 3.

When the parts are in the position shown in Fig. 1, the wire may be threaded through each die in the usual manner and wrapped about each drum 2 several times and drawing of the wire commenced. At the same time, lubricant is forced under pressure from manifold 7 through member 8 and out through orifice 12 into the die and onto the wire entering the same. The lubricant so supplied is in liquid form and may be any one of several, such as oil, oil mixed with meal or flour, or soap water. It is to be understood that the lubricant thus discharged from orifice 12 is collected in a suitable trough not shown and it is recirculated by a pump back into manifold 7 and thence out again through orifice 12.

Should one of the orifices 12 become clogged during the operation of the draw bench, a quick movement of the member 8 to the position shown in Fig. 4 will clear the same. In moving the member 8 to the position shown in Fig. 4, the reduced end 15 of the rod 14 is forced completely through the orifice 12 to clear the same of whatever foreign matter may have caused the clogging thereof. It is to be noted that when the reduced end 15 is projected through the orifice 12, the shoulder between such reduced end 15 and

the main body of the rod engages member 8 and thereby limits movement of the rod to preclude the possibility of overstressing the spring 16 and also to stop or substantially stop the flow of lubricant from the orifice. When member 8 is released, it will, through the action of spring 16, quickly snap back to its die holding and lubricating position. Thus, it is evident that such clearing of a clogged orifice can be accomplished very quickly without interrupting the continuous drawing operation.

To facilitate insertion of a die 5 to a seated position in support 3, the member 8 is provided with a face 19 at its die engaging end, which face is inclined relative to the face of the support 3 as shown in Fig. 3. When no die is seated in said support, member 8 will be urged by spring 16 into engagement with support 3. In order to insert a die 5 all that it is necessary to do is to force it laterally between the inclined face 19 of member 8 and support 3 whereby the resulting wedge action against inclined face 19 forces member 8 away from support 3. When the die 5 is in a position opposite the recess or seat 4 in support 3, the spring 16 will yieldably press the die into engagement with the bottom wall of such recess or seat. Thus, it is apparent that by reason of the inclined face 19, the insertion of a die into operative position in a support 3 is made a simple one-hand operation.

In the art of wire drawing and particularly in continuous wire drawing involving successively drawing wire through a series of dies 5 having die holes 6 of progressively reducing size it is conventional practice to make the successive dies of progressively reducing thickness as best shown in Fig. 1. Now, with the pivot axes of the members 8 disposed laterally of the associated die 5 and generally in the plane thereof as shown, there are realized several advantages which are not obtainable with the inclined sliding type of member such as disclosed in the copending application of Edwin J. McIlvried, Serial No. 632,919, now Patent No. 2,502,471, granted under date of April 4, 1950, for example, viz.:

(1) Since the axis of each member 8 is generally in the plane of the associated die, the pressure exerted by the member 8 in holding the associated die 5 in its support 3 is in a direction generally parallel to the die hole axis and transverse to the die seat. This further assures that each die will be held in its support by pressure exerted near the center thereof regardless of its thickness, the swinging of the associated member 8 not materially shifting the die engaging portion thereof laterally when the pivot axis is located generally in the plane of the die.

(2) When the member 8 is retracted as in Fig. 4 for the purpose of manipulating or inspecting the die 5, the lubricant discharge orifice is not directed at the die hole 6 whereby even in instances where the clean-out rod 14 is not employed it is unnecessary to shut off the lubricant supply or to otherwise stop the flow of lubricant.

Other modes of applying the principle of the invention may be employed, change being made as regards the details described, provided the features stated in any of the following claims or the equivalent of such be employed.

We therefore particularly point out and distinctly claim as our invention:

1. In a die holding and lubricating mechanism, the combination of a support providing a die seat, a die in such seat, a retainer formed with a passage for supplying lubricant to said die,

means supporting said retainer for movement toward and away from said die, means yieldably urging said retainer toward and into engagement with said die for exerting pressure on said die for holding it in such seat, and means operative to clear such passage in response to movement of said retainer away from and out of engagement with said die, said last named means including a rod in said retainer, and means axially constraining said rod from movement relative to said support, said rod being so disposed relative to such passage that movement of said retainer toward and away from said die effects positioning of said rod into and out of such passage respectively.

2. In a die holding and lubricating mechanism, the combination of a support providing a die seat, a die in such seat, a retainer formed with a passage for supplying lubricant to said die, means supporting said retainer for movement toward and away from said die, means yieldably urging said retainer toward and into engagement with said die for exerting pressure on said die for holding it in such seat, and means operative to clear such passage in response to movement of said retainer away from and out of engagement with said die, said last named means including a second support, a rod axially slid able in said retainer and provided with an inner end axially aligned with such passage and an outer end engaging said second support, said supports being so spaced apart that movement of said retainer toward and away from said die effects positioning of said rod into and out of such passage respectively.

3. In a die holding and lubricating mechanism, the combination of a support providing a die seat, a die in such seat, a retainer formed with a passage for supplying lubricant to said die, means supporting said retainer for movement toward and away from said die, means yieldably urging said retainer toward and into engagement with said die for exerting pressure on said die for holding it in such seat, and means operative to clear such passage in response to movement of said retainer away from and out of engagement with said die, said last named means including a second support, a rod axially slid able in said retainer and provided with an inner end axially aligned with such passage, and an outer end engaging said second support, said supports being so spaced apart that movement of said retainer toward and away from said die effects positioning of said rod into and out of such passage respectively, said rod and passage being formed with portions engageable with one another to close such passage in response to movement of said retainer away from and out of engagement with said die.

4. In a die holding and lubricating mechanism, the combination of spaced apart supports, one of said supports providing a die seat facing generally toward the other of said supports, a die in such seat, a retainer between said supports provided with a passage for supplying lubricant to said die, means supporting said retainer for movement between said supports toward and away from said die, a rod axially slid able in said retainer having an outer end adjacent said other of said supports and an inner end co-axial with such

passage, a resilient element interposed between said retainer and rod urging the former toward and into engagement with said die for exerting pressure for holding said die in such seat and the latter with its outer end in engagement with said other of said supports and with its inner end axially spaced from such passage, the inner end of said rod being so disposed relative to such passage that movement of said retainer away from and out of engagement with said die effects entry of such inner end of said rod into such passage.

5. In a die holding and lubricating mechanism, the combination of spaced apart supports, one of said supports providing a die seat facing generally toward the other of said supports, a die in such seat, a retainer between said supports provided with a passage for supplying lubricant to said die, means supporting said retainer for movement between said supports toward and away from said die, a rod axially slid able in said retainer having an outer end adjacent said other of said supports and an inner end co-axial with such passage, a resilient element interposed between said retainer and rod urging the former toward said die to a position retaining said die in such seat and the latter with its outer end in engagement with said other of said supports and with its inner end axially spaced from such passage, the inner end of said rod being so disposed relative to such passage that movement of said retainer away from such position retaining such die in such seat effects entry of such inner end of said rod into such passage.

6. In a die retaining and lubricating mechanism for wire drawing apparatus, the combination of a support providing a die seat, a die in such seat formed with a face opposed to such seat and with a die hole transversely through such face, a retainer formed with a portion thereof disposed to one side of such die hole and adapted to engage such die face to hold said die in its seat and with a passage directed at the die hole for supplying lubricant to said die, means supporting said retainer for pivotal movement about an axis located in radially spaced relation to the die engaging portion of said retainer and generally in the plane of such die face whereby said retainer may be swung about such axis directly toward and away from said die with the latter disposed between the die engaging portion of said retainer and such seat, and spring means acting on said retainer to urge the die engaging portion thereof toward and into engagement with said die for exerting pressure on said die for holding it in such seat.
